DESIGN FOR A COMBINED FLUID PRESSURE TANK AND STAND

Clark F. Walsh, Charles City, Iowa

Application August 26, 1947, Serial No. 141,074

Term of patent 3½ years

(CL. D62—2)

To all whom it may concern:

Be it known that I, Clark F. Walsh, a citizen of the United States, residing at Charles City, county of Floyd, and State of Iowa, have invented a new, original, and ornamental Design for a Combined Fluid Pressure Tank and Stand, of which the following is a specification, reference being had to the accompanying drawing, forming part thereof.

Fig. 1 is a front perspective view of a combined fluid pressure tank and stand embodying my new design;

Fig. 2 is a side elevational view of the same; and Fig. 3 is a top plan view of the same.

I claim:

The ornamental design for a combined fluid pressure tank and stand, as shown.

CLARK F. WALSH.
